UNITED STATES PATENT OFFICE.

ALBERT E. MULLEN, OF NEW YORK, N. Y.

CONTAINER.

Application filed April 16, 1927. Serial No. 184,332.

My invention relates to containers and refers particularly to containers adapted for the carrying of powder compacts, rouges and similar toilet preparations.

5 In devices of this character it is essential that they be compact and of such construction that the several commodities carried therein should be readily accessible.

It is further desirable that they should 10 carry a mirror capable of use with each of the several contents.

It is further desirable that the device should be of such construction as to allow of the easy removal of used compacts and the 15 insertion of new ones.

My device contains all of the above and other desirable qualities, as will be evidenced upon a consideration of my specification and its accompanying drawings.

20 In the accompanying drawings illustrating one form of the device of my invention similar parts are designated by similar numerals.

Figure 1 is a perspective view of one form 25 of my device in closed position.

Figure 2 is an enlarged view of the device of Figure 1, in wide open position exposing the contents of the bottom member.

Figure 3 is the device of Figure 2 in wide 30 open position exposing the contents of the top member.

Figure 4 is a cross-section through the line 4—4 of Figure 3.

Figure 5 is an enlarged cross-section 35 through the line 5—5 of Figure 1.

Figure 6 is a cross-section through the line 6—6 of Figure 3.

Figure 7 is a cross-section through the line 7—7 of Figure 3.

40 Figure 8 is a perspective view of the bottom compact holder.

Figure 9 is a perspective view of the top compact holder.

Figure 10 is a perspective view of the 45 rouge holder with the cover raised.

The particular form of the device of my invention shown in the accompanying drawings comprises a bottom member having the bottom 50 10, the sides 11 and 12 and the ends 13 and 14. Within the bottom member is a tray compact holder having the bottom 15, the sides 16 and 17 and the ends 18 and 19 carrying the compact 20. This compact holder is maintained within the bottom member by frictional contact between the sides of the compact member and the sides of the bot-

tom member and also by means of the extended locking member 21 carried by the end 14 of the bottom member and extending over the top of the end 19 of the compact holder. 60

Spaced from the end 18 and fixedly attached to the inner face of the bottom end 13 is a member 54, each bent end of which has an upwardly extending member 55 acting as a guide for the top member when being 65 closed, the ends 56, 56 of the member 54 abutting upon the end 18 of the compact holder to maintain it in position.

A top member of the device comprises a top 22, sides 23 and 24 and the ends 25 and 70 26. The end 14 of the bottom member and the end 25 of the top member, or cover, are pivotally connected at 27.

Within the top member is a smaller tray compact holder having the bottom 29, the 75 sides 30 and 31 and the ends 32 and 33 and carrying the compact 34.

This top compact holder is held in place by frictional contact of its sides with the sides of the top member and by means of the 80 locking member 35 carried by the top member end 25.

Within the top member and within the space between the end 32 of the compact holder and the end 26 of the top member 85 is a tray rouge holder having the bottom 36, the sides 37 and 38, the ends 39 and 40 and the hinged cover 41, and carries a rouge compact 42. The cover 41 carries the extension 43 for ease of opening and for holding a 90 powder puff upon the compact 42.

The rouge holder is maintained in position within the top member by means of extensions 44 and 45 carried by the sides 23 and 24 of the top member which are inserted 95 within the longitudinal recesses 46 and 47 of the sides 37 and 38 of the rouge holder. As the rouge holder is somewhat smaller longitudinally of the top member than the space within which it is positioned it may be moved therein to allow the smaller tray compact holder to be moved from release from the locking member 35 and thus made capable of removal from the top member.

A metallic mirror 48 is hingedly attached 105 to the hinged jointure of the top member and bottom member.

A powder puff 49 is inserted in the bottom member and a powder puff 50 is inserted in the top member. 110

The device is maintained in closed position by means of the spring locking means

51, the extended pin portion 52 of which engages the opening 53 of the top end 26.

The operation of my device is as follows:—

5 When the device is in the position shown in Figure 2, but with the top member at right angles to the bottom member, access is given to the compact in the bottom member and the mirror is in position for use.

10 When the device is in the position shown in Figures 3 and 4, but with the bottom member at right angles to the top member, compact and the rouge in the top member are accessible and the mirror is in position for

15 use. When in this position the rouge receptacle cover may be closed if the rouge is not needed.

20 The ease with which used compacts may be removed and new ones introduced has been explained above.

25 A particular feature of my device is the fact that it may be readily held in one hand with the compact and mirror in proper position for use.

30 Another feature of my device is its compactness, due to the abutment of the bottom member and top member when closed and further because of the extreme thinness of the metallic mirror.

35 I do not limit myself to the particular size, shape, number, arrangement or material of parts as shown and described, as these are given simply as a means for clearly describing my invention.

40 What I claim is:—

1. In a container, in combination, a bottom member, a removable tray compact holder within the bottom member spaced from one end thereof, a top member hingedly attached to the bottom member, a removable tray compact holder within the top member, a separate removable tray rouge holder within the top member, spaced from one end thereof and capable of longitudinal movement within the top member and a metallic mirror carried by the top and bottom hinge capable of covering the interior of the top member and bottom member.

45 2. In a container, in combination, a bottom member, a removable tray compact holder within the bottom member spaced from one end thereof, a compact holder locking member carried by the bottom member, a top member hingedly attached to the bottom member, a removable tray compact holder within the top member, a compact holder locking means carried by the top member, a removable tray rouge holder within the top member spaced from one end thereof, a hinged cover for the rouge holder, and a pivotally attached metallic mirror capable of covering the interior of the top member and the bottom member.

50 holder within the top member spaced from one end thereof and capable of longitudinal movement within the top member, a hinged cover for the rouge holder, and a metallic mirror carried by the top and bottom member hinge capable of covering the interior of the top member and the bottom member.

55 3. In a container, in combination, a bottom member, a removable tray compact holder within the bottom member spaced from one end thereof, a top member hingedly attached to the bottom member, a removable tray compact holder within the top member, a removable tray rouge holder within the top member, spaced from one end thereof, means within the bottom member guiding the top member and bottom member during the closure of the device and a metallic mirror carried by the top and bottom hinge capable of covering the interior of the top member and bottom member.

60 4. In a container, in combination, a bottom member, a removable tray compact holder within the bottom member spaced from one end thereofon, a compact holder locking member carried by the bottom member, acting as a guide for the top member and bottom member during the closure of the device, a top member hingedly attached to the bottom member, a removable tray compact holder within the top member, a compact holder locking means carried by the top member, a removable tray rouge holder within the top member spaced from one end thereof, a hinged cover for the rouge holder, and a metallic mirror carried by the top and bottom member hinge capable of covering the interior of the top member and the bottom member.

65 5. In a container, in combination, a bottom member, a removable tray compact holder within the bottom member spaced from one end thereof, a compact holder locking member carried by the bottom member, a top member hingedly attached to the bottom member, a removable tray compact holder within the top member, a compact holder locking means carried by the top member, a removable tray rouge holder within the top member spaced from one end thereof, a hinged cover for the rouge holder, and a pivotally attached metallic mirror capable of covering the interior of the top member and the bottom member.

70 Signed at New York in the county of New York and State of New York this 18th day of March, 1927.

ALBERT E. MULLEN.
